CONVERTIBLE CHAIR LOUNGE

Alexander J. Duke, Los Angeles, Calif.

Application September 18, 1951, Serial No. 16,678

Term of patent 14 years

(Cl. D15—11)

To all whom it may concern:

Be it known that I, Alexander J. Duke, a citizen of the United States of America, residing in the city of Los Angeles, in the county of Los Angeles, State of California, have invented a new, original, and ornamental Design for a Convertible Chair Lounge, of which the following is a specification, reference being had to the accompanying drawing, forming a part thereof.

Fig. 1 is a front left perspective view of a convertible chair lounge in its folded position, showing my new design;

Fig. 2 is a front right perspective view of the same in its extended position;

Fig. 3 is a rear elevational view thereof;

Fig. 4 is a bottom view of my convertible chair lounge in its extended position;

Fig. 5 is a perspective view similar to Fig. 1, but with the door open and a portion of the front of the movable section broken away to show the abutting edges of the movable section and the base portion; and

Fig. 6 is a side elevational view of my convertible chair lounge.

I claim:

The ornamental design for a convertible chair lounge, substantially as shown and described.

ALEXANDER J. DUKE.
